UNITED STATES PATENT OFFICE.

LUCY A. WALKER, OF BERKELEY, CALIFORNIA.

CORSET BELT OR GIRDLE.

1,256,850.

Specification of Letters Patent. Patented Feb. 19, 1918.

Application filed May 22, 1917. Serial No. 170,238.

To all whom it may concern:

Be it known that I, LUCY A. WALKER, a citizen of the United States, residing at Berkeley, in the county of Alameda and State of California, have invented certain new and useful Improvements in Corset Belts or Girdles, of which the following is a specification.

This invention relates to women's undergarments, and more particularly to corsets.

10 The primary object of the invention is to provide a belt of this character so constructed as to impart to the wearer a neat waist line and relatively straight front without 15 any restraint being exerted thereby on the body in turning, bending, stooping or the like.

Another object is to so construct a belt of this character to furnish means for securing 20 and supporting shirt waists, skirts, trousers, hose and the like.

Another object is to so construct a device 25 of this character as to cause it to distribute pressure upon the hips of the wearer and prevent any disagreeable cutting into the flesh and which does not in any way interfere with the freedom of the motion of the body.

With the foregoing and other objects in 30 view, which will appear as the description proceeds, the invention resides in the combination and arrangement of parts and in the details of construction hereinafter described and claimed, it being understood 35 that changes in the precise embodiment of the invention herein disclosed may be made within the scope of what is claimed without departing from the spirit of the invention.

In the accompanying drawings:—

40 Figure 1 represents a perspective view of one form of this improved belt shown applied,

Fig. 2 is a front elevation of the girdle with the front section removed,

45 Fig. 3 is a rear elevation shown applied, and

Fig. 4 is a front elevation shown applied of a slightly different form of the girdle.

In the embodiment illustrated in Figs. 1 50 and 2, the girdle or belt 1 constituting this invention is shown constructed of a strip of webbing or woven belting 2 of a length greater than the circumference of the waist of the wearer for which it is designed, said

belts being made in different sizes in the 55 same manner that corsets are, to fit different sized waist measures.

One end of this strip 2 carries a buckle 3 with which its other end is designed to be detachably and adjustably engaged. (See 60 Fig. 1.)

Buttons or other suitable fasteners 4 are preferably carried by the strip 2 for the engagement by coöperating fasteners on the inside of the shirt waist band or dress skirt 65 band.

The stiffening and supporting means for this girdle are constructed of what are known on the market as "corset shields", and which are made in the form shown at 5, each 70 including a longitudinally extending casting 6 having on opposite sides thereof alined pockets 7 in which are incased stiffening strips 8 of steel, whalebone, or the like, forming fingers or stems which extend transversely of the girdle and longitudinally of the wearer when applied.

These shields or sections 5 may have any desired number of fingers or stems, five being preferably used in each section. 80

The fingers or stems which are arranged on the upper side of the fabric strip 2 are made shorter than those on the lower side thereof and the fingers of each strip on the lower side decrease in length from the middle toward the ends of the strip as is shown clearly in Fig. 2, so that when these sections are applied to the strip 2, which is preferably accomplished by means of safety pins 9, the longer fingers will be positioned one at 90 the center of the back of the wearer and others over the hips as is shown clearly in Figs. 1 and 3 to hold down the flesh at these points. The fingers on the lower side of the belt are preferably provided with fasteners 95 10 which may be in the form of snaps, buttons or the like, but which are designed to be connected to the bands of skirts when it is desired to attach them below the waist line. These fasteners 10 are here shown arranged 100 on every other finger, although obviously they may be carried by every finger if found desirable.

In the form shown in Figs. 1 and 2, the front section 11 of the belt is formed of a 105 shield similar to the other sections, except that the fingers thereof on both sides of the strip 2 to which it is attached, are made short

and are here shown of the same length although obviously they may be varied if found desirable.

In the use of this belt, the strip 2 having 5 been attached to the sections 5 and 11 by the safety pins 9 on the outside of said sections as is shown clearly in Fig. 2, the belt may be placed around the waist of the wearer and secured in adjusted position thereon by en- 10 gaging the free end of strip 2 with the buckle 3 carried by the other end thereof, the belt being tightened at the discretion or according to the wishes of the wearer.

From the above description it will be seen 15 that a belt of this character is especially desirable for use by short-waisted, stout women when it is found desirable for any reason to omit the corset and thereby conform to the comfort of the wearer while at 20 the same time enabling her to present a neat, tidy appearance, preventing the skirt bands from cutting into the waist which is very unsightly as well as uncomfortable.

In the form shown in Fig. 4, the front section 25 11 shown in the other figures is substituted by an abdominal pad 12 which is provided at its upper corners with buckles 13 designed to be detachably and adjustably engaged with the opposite ends of the fabric strip 2. Elastic garters 14 are secured to the 30 lower edge of this pad, any desired number of which may be employed, four being here shown and which are equipped with the usual hose engaging clamps 15 and slides 16.

It will thus be seen that this pad 12 may 35 be properly positioned to support the abdo-

men and that pressure may be regulated thereon by means of the elastic garters 14.

From the foregoing description, taken in connection with the accompanying drawings, the advantages of the construction and of the method of operation will be readily apparent to those skilled in the art to which the invention appertains and while I have described the principle of operation of the 40 invention together with the device which I now consider to be the best embodiment thereof, I desire to have it understood that the device shown is merely illustrative and that such changes may be made as are with- 45 in the scope of the claimed invention.

I claim:—

A corset belt comprising a fabric strip having stiffening fingers extending laterally from opposite sides thereof, said fingers on the upper side of said strip decreasing in length from the center toward the opposite ends of the strip, said fingers being free from their centers to their terminals, the fingers on the lower side of said strip varying in length with the longer ones disposed to be positioned at the center of the back and over the hips of the wearer when the belt is applied to hold down the flesh at these points and means for adjustably connecting the 60 ends of the belt.

In testimony whereof I affix my signature in presence of two witnesses.

LUCY A. WALKER.
